ABSTRACT

A display frame comprises exterior shelf units. The frame has interior shelf units which slidably and directly engage with each other and the exterior shelf units. The frame also comprises exterior connectors for connecting the exterior shelf units and the interior connectors. The interior connectors are hash shaped and oriented at an angle with respect to the vertical plane of the display frame and the sliding together of the exterior shelf units with the hash shaped connectors are used to expand display shelf frame. The exterior shelf units and the interior shelf units are slideably engaged with each other.

EXPANDABLE DISPLAY FRAME

BACKGROUND OF THE INVENTION

1. Field of the Invention

The present invention relates to the furniture industry and, more particularly to a frame which is well adapted for displaying miniature figurines.

2. Description of Related Art

Plastic construction toys are manufactured by The Lego Group, among other companies. These toys comprise interlocking plastic bricks and also miniature figurines adapted to interface with the studs on the plastic Lego bricks. Many Lego enthusiasts like to have display stands for their miniature figurines.

However, there currently is no aesthetically pleasing versatile plastic display frame for miniature figurines which have: (1) integral studs for holding the miniature figurines, (2) which are expandable to any custom size and (3) which can also be readily flat packed for postage.

If the display stand is not able to be flat packed, then it would not be economically feasible for it to be posted to customers. That is, the stand would take up too much volume, which would increase the costs of postage to an unprofitable level.

If the display stand is not expandable, the user could not expand the stand to accommodate their growing collection of items for display.

The object of the present invention is to provide an aesthetically pleasing, versatile, plastic display frame which is expandable to any custom size and which can also be readily flat packed for postage.

SUMMARY OF THE INVENTION

According to the present invention, there is provided a display frame comprising:

- (a) exterior shelf units;
  - (b) interior shelf units which slidably and directly engage with each other and the exterior shelf units;
  - (c) exterior connectors for connecting the exterior shelf units; and
  - (d) interior connectors;
- wherein the interior connectors include hash shaped connectors oriented at an angle with respect to the vertical plane of the display frame and the sliding together of the exterior shelf units with the hash shaped connectors are used to expand the display frame.

Preferably, the exterior shelf units and the interior shelf units are slideably engaged with each other. The interior connectors preferably include center piece connectors and linking connectors.

The exterior shelf units may have lamps to illuminate a transparent back panel. Preferably, the transparent back panel has etching to direct the light from the lamps.

The frame may include a dust cover which is magnetically connectable to the frame.

The interior shelf units preferably have studs for engaging with miniature figurines.

BRIEF DESCRIPTION OF THE DRAWINGS

Embodiments of the invention will be described with reference to the following drawings, in which:

2

FIG. 1 is a front view of a frame according to an embodiment of the present invention.

FIG. 2 is a perspective view of the front and back of an interior shelf of the frame of FIG. 1.

5 FIG. 3 is a perspective view of an exterior shelf of the frame of FIG. 1.

FIG. 4 is rear view of four frames of FIG. 1 conjoined together.

10 FIG. 5 is an exploded view of a frame according to an embodiment of the present invention.

FIG. 6 is a side view of the frame of FIG. 1.

FIG. 7 is a perspective view of a first end of an exterior connector for the frame of FIG. 1.

15 FIG. 8 is a perspective view of a second end of the exterior connector of FIG. 7.

FIG. 9 is a perspective view of the exterior connector of FIGS. 7 and 8 in position within the frame of FIG. 1.

20 FIG. 10 is a perspective view of an interior hash shaped connector for conjoining frames as shown in FIG. 2.

FIG. 11 is a perspective view of the interior hash shaped connector of FIG. 5 in position within the frame.

25 FIG. 12 is a perspective view of a first end of a linking connector for the conjoined frame of FIG. 2.

FIG. 13 is a perspective view of a second end of the linking connector of FIG. 10.

30 FIG. 14 is perspective view of the linking connector of FIGS. 10 and 11 in position within the frame of FIG. 2, showing the light ribbon connection through a channel in the linking connector

DETAILED DESCRIPTION OF THE INVENTION

FIG. 1 shows the rear side of a display frame 10 according to an embodiment of the present invention.

The frame has interior shelf units 12 (shown in isolation in FIG. 2) and exterior shelf units 14 (shown in isolation in FIG. 3) which are all slidably engageable with each other.

Multiple frames 10 can be conjoined together to expand 40 the shelf space, as shown in FIG. 4.

The frames 10 comprise exterior connectors 16 (see FIGS. 7, 8 and 9) and two types of interior connectors, namely the hash shaped connectors 18 (see FIGS. 10 and 11) and linking connectors 20 (see FIGS. 12, 13 and 14).

45 If the user wants to join multiple frames together (as shown in FIG. 4) then they can replace an exterior connector 16 with a hash shaped connector 18 to slidably engage another exterior shelf unit 14. Thereby, the display frame 10 of the present invention is expandable, unlike prior art display frames. This makes a substantial contribution to the working of the invention.

The frame 10 can be used for displaying Lego brand 50 miniature figurines 22 (see FIG. 1). Hence the interior shelf units have studs 24 for interfacing with holes in the feet of the miniature figurines 22.

Referring to FIG. 5, the base exterior shelf unit 14 has a slot 26 for a transparent backing panel 28. The base exterior shelf unit 18 has lamps 30 spaced regularly along it. The lamps 30 shine through the transparent backing panel 28 to 55 provide an aesthetically pleasing aspect to the display frame 10. The transparent backing panel 28 can have etching to direct the light through the panel 28 in any particular way. For example, the etching could be an outline of a miniature figurine. As shown in FIG. 14, connectable lighting ribbons 32 bridge over the linking connectors 20 adjoining the exterior shelf units 14. The lighting ribbons 32 provide power to the lamps 30 via a USB-C input cable 34.

As shown in FIG. 5, the frame 10 has a cover 36 which is magnetically connectable to the frame 10.

The present invention thereby provides an aesthetically pleasing, versatile, plastic display frame which is expandable to any custom size, and which can also be readily flat packed for postage.

In the present specification and claims (if any), the word 'comprising' and its derivatives including 'comprises' and 'comprise' include each of the stated integers but does not exclude the inclusion of one or more further integers.

Reference throughout this specification to 'one embodiment' or 'an embodiment' means that a particular feature, structure, or characteristic described in connection with the embodiment is included in at least one embodiment of the present invention. Thus, the appearance of the phrases 'in one embodiment' or 'in an embodiment' in various places throughout this specification are not necessarily all referring to the same embodiment. Furthermore, the particular features, structures, or characteristics may be combined in any suitable manner in one or more combinations.

In compliance with the statute, the invention has been described in language more or less specific to structural or methodical features. It is to be understood that the invention is not limited to specific features shown or described since

the means herein described comprises preferred forms of putting the invention into effect. The invention is, therefore, claimed in any of its forms or modifications within the proper scope of the appended claims (if any) appropriately interpreted by those skilled in the art.

The invention claimed is:

1. A display frame comprising:
  - (a) exterior shelf units;
  - (b) interior shelf units which slidably and directly engage with each other and the exterior shelf units for supporting and displaying items on or between the interior shelf units, wherein the interior shelf units include studs for engaging with miniature figures;
  - (c) exterior connectors for interconnecting the exterior shelf units to each other; and
  - (d) interior connectors; wherein the interior connectors include hash shaped connectors oriented at an angle with respect to a frame width and a frame height of the display frame and the exterior shelf units are joined together with the hash shaped connectors by sliding so that the frame width or frame height of the display frame can be expanded.
